UNITED STATES PATENT OFFICE.

HUDSON BROWN, OF CHICAGO, ILLINOIS.

RAILROAD GATE.

Application filed October 6, 1922, Serial No. 592,786. Renewed August 13, 1923.

To all whom it may concern:

Be it known that I, HUDSON BROWN, a citizen of the United States, residing at Chicago, in the county of Cook and State of Illinois, have invented new and useful Improvements in Railroad Gates, of which the following is a specification.

The present invention has reference to a railway crossing gate.

10 The object is to produce a simple means whereby a gate will be automatically swung to road closing position by a train approaching a crossing and returned to open the roadway after the train has passed the crossing.

15 The foregoing, and many other objects which will appear as the nature of the invention is better understood, may be accomplished by a construction, combination and operative arrangement of parts such as is illustrated by the drawings. It is to be understood, however, that the drawings merely illustrate a satisfactory embodiment of the improvement and that I am entitled 20 to all changes therefrom and to such modifications as fall within the scope of the claims.

In the drawings:—

Figure 1 is a top plan view of the improvement.

30 Figure 2 is a side elevation, with the gate in its elevated position.

Figure 3 is a similar view with the gate in its lowered position.

35 Figure 4 is a sectional view approximately on the line 4—4 of Figure 1, on an enlarged scale.

Figure 5 is an enlarged sectional view approximately on the line 5—5 of Figure 1.

40 Figure 6 is a similar view showing one of the springs depressed by a wheel of the rolling stock.

Figure 7 is a plan view of the construction shown in Figure 5.

45 Figure 8 is a view showing the wheels of a truck engaging the spring, the rails being in section.

Figure 9 is a transverse section showing the gate open.

50 Figure 10 is a similar view with the gate closed.

Figure 11 shows the application of the improvement on a double track.

Figure 12 is a view similar to Figure 11, but illustrating a modification.

55 Figure 13 is a section on line 13—13 of Figure 12.

Figure 14 is a similar view with the gates open.

Figure 15 is an elevation of the compensating means.

60 Figure 16 is a view showing a means whereby the gates may be raised on a single track by a train passing the crossing.

In the drawings, the numeral 1 designates a railway track, and 2 a road crossing the 65 track.

Outward of two of the opposite corners of the crossing there are platforms 3. On each of the platforms there are spaced upright boxings 4. These boxings have bearing openings 5 for the shafts 6 which extend toward the track. The shafts have both square and round portions, and one of the square portions of each of the said shafts is disposed between the bearing boxings 5. 70 Secured to one of the square sides of the said portions of each of the shafts 6 is a plate 7. These plates are designed to normally rest on upright stop members 8 that are secured on the platforms 3. On the 75 outer end of each of the plates 7 is a right angular socket 9. In each of the sockets there is secured a gate 10. Pivoted adjacent the outer end of each gate 10 is a leg 11. These legs are designed to contact with the ground and to support the gates when the latter are swung transversely of the crossing 80 2.

At the ends of the shafts 6 nearest the track 1 are bearing boxes 12 that are secured 90 to platforms 3.

On the outer square end of each of the shafts 6 is a head plate 14. The head plate, at diagonally opposed points has outstanding 95 studs 15.

Pivotedly secured to each of the studs 15 of the respective head plates 14 are oppositely extending rods 16. Each of the rods comprises two sections that are retained in longitudinal alignment by and connected together with a helical spring 17. Preferably, the helical springs 17 have one end secured in a socket 18 Figure 4 in one of the sections of the rod 16, and its other end secured on the inner portion of a reduced 100 finger 19 that enters the socket 18, said finger being an integral extension of the other rod 16.

The outer ends of the rod 16 are loosely connected, as at 20, to arched contact members 21 which are preferably in the nature of springs and the said springs 21 are dis-

posed adjacent to but normally below the heads of the rails 22 of the track 1, and at the outer sides of the said rails.

The contact springs 21 have one of their ends secured to yoke members 23, and the arms of the yokes are slotted, as at 24, and are disposed on the sides of a slideable box-like member 25. Suitable studs 26 pass through the slots 24 and enter the sides of the box. The box has its floor provided with an angle depressed or cammed portion 27, and in this depression the free end of the contact member 21 normally rests, and as a consequence the said member is retained below the level of the head of the rail 22. Connected by a rod 28 to an outer arched spring contact 29 is the yoke 23. The free end of the spring 29 is secured on a suitable support 30, and the rod 28 is constructed of sections which are connected by a spring 31. To the end of each of the box members 25 is a rod 32. Each of these rods is constructed of two sections connected by a spring 33. Each of the rods 32 is connected to the free end of an arched spring contact member 34. The free end of the spring 34 is secured on a suitable support 35. The connection between the rods and all of the spring contact members is in the nature of a loose or swiveled joint, and the spring members 34 and 29 have their central portions normally projected above the level of the rails of the track 1. The box members rest upon suitable supports, and all of the construction is designed to be protected from the elements either by arranging the same in suitable casings, or by treating the same with a preservative. It is, of course, to be understood that the contact members are necessarily partly exposed, and the operation of the device may be briefly described as follows:—

A train approaches the crossing in either direction, and for the sake of convenience we will suppose the train approaches in the direction of the arrow in Figure 1 of the drawings. As stated, the gate throw contact members 21 are normally below the level of the track rails, and consequently will not be contacted by the tread portions of the wheels of a train. The wheels, however, will first engage with the contact members 29, depressing the same, causing the rods 30 thereof to slide the boxes 25 that are connected with the said rods to bring the free ends of the gate throw contact members 21 out of the depressions 27 and on to the elevated portion of the bottom of the said box. This brings the members 21 in position to be engaged by the wheels of the passing train. We will suppose the train has passed off of the contact member 21, permitting the same to return to initial position. The return of this spring expands the rod 30 without sliding the box member 25 to bring the

gate throw contact members 21 below the lever of the track. The car wheels passing on to the contact members 21 will cause the same to exert a pushing action on its rod 16 and turn the shaft 6 one-half of a revolution. This swings the gates to closed position. The wheels of the train now engage with the track contact members 34, causing said members to exert a pushing action on either one of the rods 32 to influence the boxes to bring the free ends of the springs in the depressed portions of the boxes. It is to be understood that the leg of the gate is in contact with the ground, and this movement will simply cause the expansion of the rods 16 without further influencing the gate or, if any influence is exerted, the same will cause the leg to more tightly contact with the ground. The action of the contact members on one side of the crossing will expand the rod 16 of the gate throw contact members on the opposite sides of the crossing, but will not otherwise influence the said contact members. The train now passes the crossing on to the contact members 34 which will cause the same to exert a pushing action on their rods and move the box-like members 25 to elevate the gate throw contact members 21 on the second end of the crossing. When the wheels of the train travel over the said contact members 25, the latter will be depressed and exert a pulling action on their rods, which will turn the shaft 6 for one-half of a revolution in a direction reversely to that which it has been first turned, and consequently swing the gate to its open position. As the train travels further and engages the next contact member 29 the same will, through the medium of its rods move the yoke which influences the box-like member 25 to return the same to initial position, bringing the free end or spring in the depressed portions of the box. It will thus be noted that the device will operate with equal efficiency when a train travels in either direction on the track, that few, simple, strong and efficient parts are employed, and that the action is entirely automatic.

I have illustrated the application of the improvement on a double track in Figure 12. As the construction is similar to that previously described, the reference characters indicating the parts previously set forth may be considered applicable to the construction disclosed in the said figure. The weighted ends of the gates automatically swing the same to their elevated or non-obstructing position. The shaft connecting the gates is extended between the rails of both tracks, one shaft connecting both gates. This shaft is suitably housed. It will be apparent that a train traveling in the direction of the arrow X on the track 50 will depress the spring, in a manner as previously described, which will, of course,

simultaneously influence both of the gates to a lowered or obstructing position. When the train has passed the crossing, the gates will be returned to initial position by their 5 weights, as previously stated. In a like manner, the train traveling on the track 51 will depress the springs to revolve the shaft to swing both the gates Y and Z to closed position, and after leaving the crossing the 10 gates will be returned to initial position.

In Figures 12, 13 and 14, I have illustrated a modification in which the number of parts employed is reduced and the construction generally simplified. In these 15 figures there is arranged at each corner of the crossing 51 opposed gates of a somewhat different construction than those previously described. Each of these gates includes a gate bar 52 designed, when in obstructing position 20 to rest upon air cushioned rods 53 whereby the gates will be held horizontally when swung to obstructing position and also whereby injury to the gates and the operating means for the gates will be obviated. 25 A bar 52 of each gate is provided with a bell 52' designed to sound an alarm when the gates are swung, and in addition thereto each gate is provided with a visible signal such as an electric bulb designed to be lighted 30 when the gates are operated in the night time.

Each gate bar has secured thereto the upper angle end 54 of a lever 55. Each lever has 35 its upper angle end at its outer corner provided with ears between which there are pivoted extensions 56, and these extensions are designed to rest on uprights or posts 57 when the gates are in obstructing position, the said posts breaking the hinged 40 joints between the links and lever, whereby the said gates will be swung angularly substantially in a plane with the levers 55 against the post 57 to support the gates in non-obstructing position.

45 Each lever is connected to a shaft 58 arranged longitudinally of the crossing 51 and beneath the rails of the tracks 59. The spaced levers are journaled in suitable bearings and each lever, at diagonally opposed 50 points with respect to the crossing has secured thereon a cam head 60. The heads 60 are preferably constructed of two sections whereby the same may be bolted around the shafts, and each head has its 55 opposed edge grooved to receive therein the sectional rods 61 and 62 respectively, the connection between the rods 61 and 62 being in the nature of springs 63 so that the said rods are of a construction similar to 60 that previously described. The opposed rods 61 and 62 are guided in bearings 64 against the outer sides of the rails of the respective tracks 59 whereby the ends thereof will be effectively sustained in the opposed grooves of the head 60. The rods 65

61 and 62 are connected to the ends of arched springs 65 and 66 respectively, and the depression of either of these springs will move one of the rods longitudinally to cause the same to contact with the wall of 70 the groove in the head 60 and turn one of the shafts so that one of the gates on each side of the crossing will be brought to obstructing position.

In order that all of the gates will work 75 in unison, I arrange between the tracks 59 shaft motion transmitting means of a particular and peculiar construction, the same being illustrated in detail in Figure 15 of the drawings. On each shaft, at the center thereof there is secured a pair of cam heads 80 67 respectively. Each of the heads 67 is constructed of two parts bolted together to effect a connection therebetween and a binding on the shafts. These heads 67 have their confronting faces grooved, the outer walls of the grooves being straight and the inner walls thereof being rounded, and these grooves provide pockets for rods 68 and 69 85 respectively. By reference to Fig. 15 it will be seen that the rods are disposed at opposite angles and while not in contacting engagement, cross each other at the center thereof. Suitable supporting means is provided for the rods, and it will be apparent 90 that when one of the shafts is turned the heads 67 on the said shaft will be likewise turned to impart a motion to one of the rods which is forced into the pocket of the opposed head 67 to cause the second shaft 58 95 100 to turn in unison with the first mentioned shaft. Thus it will be noted that a train traveling in either direction on either of the tracks will simultaneously swing both of the shafts 58, with the result that both of the gates will be operated. By arranging 105 the arched springs 65 and 66 on the sides of the outer rails of the respective tracks and at points suitably spaced from the crossing, the rim of a car wheel will contact with the arched spring nearest thereto to operate the shafts to swing the gates to closed position and after passing the crossing the second arched spring will be likewise contacted to reverse the turning of the 110 shafts and consequently bring the gates to open position.

115 There are instances in which a train is made up of few coaches and the arched springs may be placed such distance from the crossing that the train will have completely passed thereover and traveled a distance away therefrom before the gates are 120 swung to open position, and therefore I have illustrated in Figure 16 of the drawings, a single track construction in which there is an arched spring 70 disposed centrally of the crossing and provided with rod sections 71 connected by a spring 72, the outermost rod being received in the groove of 125 130

a cam head 73, similar to that previously described, and the said cam being fixed on a shaft 74 that is connected with a gate. Thus when the wheels of the last coach pass centrally over the crossing, the arched member will be operated to swing the shaft to move the gate to open position. In this connection it is to be understood that the mechanism heretofore referred to is also employed so that while the spring may be constantly depressed by the wheels of the truck, the same will not influence the gate until the wheels of the truck have ceased to depress the arched spring similar to the 10 springs 65 or 66.

It is believed that the foregoing description, when taken in connection with the drawings will fully set forth the construction and operation of the improvement to 20 those skilled in the art to which this invention relates. It is to be understood, as previously stated, that all modifications other than those illustrated may be resorted to, providing the same fall within the scope 25 of the claims without departing from the spirit of the invention, and it is to be further understood that I am not to be restricted to the precise location of parts and also that as much as possible of the operating parts may be housed to protect the 30 same from weather conditions.

Having thus described the invention, what I claim is:

1. In a pivoted crossing gate adapted to 35 be operated by a train passing the crossing, gate throw means located to one side of the crossing normally out of train engaging position, means in advance of said throw means engaged by the train for bringing the throw means to train engaging position and for causing the latter to swing the gate, means between the crossing and the gate throw means for returning the latter to initial position without influencing the 40 gate, gate throw means on the opposite side of the crossing out of train engaging position and designed to swing the gate to a second position, means between said throw means and the crossing actuated by the train for bringing the throw means to train engaging position and for swinging the gate, and means actuated by the train arranged outward of the said throw means for returning the latter to initial position.
2. In a pivoted crossing gate designed to 50 be operated by a train passing the crossing, oppositely extending flexible means connected to the gate, yieldable gate operating means normally out of the path of engagement of the train connected to said flexible means, yieldable means having flexible elements associated therewith directed to the gate, throw means designed when the outer yieldable means to one side of the crossing 55 is engaged by a train, to bring the gate

means thereof adjacent thereto in train engaging position to cause the latter to swing the gate to one position, and when the yieldable means between the said throw means and the crossing is contacted by the train to return the throw means to initial position without influencing the gate, and thereafter, when the train passes the crossing and contacts with the yieldable means adjacent thereto to bring the second throw means in train engaging position to permit of the latter swinging the gate to initial position, and outer yieldable means, when contacted by the train, designed to return the last mentioned throw means to initial position without further influencing the gate.

3. In a pivoted crossing gate which is adapted to be operated by a train passing the crossing, yieldable throw means located to one side of the crossing, flexible means connecting the throw means with the gate, and said throw means being normally out of train engaging position, compressible means in advance of said throw means, flexible means associated therewith and connected with means disposed below the throw means and designed when engaged by a train to influence said last mentioned means to elevate the throw means to train engaging position to permit the latter influencing the flexible means between the same and the gate to swing the gate, gate throw means to the opposite side of the crossing, flexible means between said last mentioned throw means and the gate, yieldable means between the last mentioned throw means and the crossing, flexible means connected therewith and associated with means disposed below the throw means and designed when engaged by a train to actuate the latter to bring the throw 100 means to train contacting position to permit of the latter influencing the flexible means associated therewith for returning the train to initial position, and yieldable means arranged outward of the last throw means and in the path of contact with the train and connected with the means for elevating the throw means, and designed to operate the latter to return the throw means to initial position, without further influencing the gate, when the last mentioned means is engaged by the train.

4. In a pivoted crossing gate adapted to be operated by a train passing the crossing, including an arched spring throw member normally out of train engaging position, yieldable means connected thereto and to the gate, slidable means between the throw means, means in advance of said throw means and connected with the slidable means designed to be engaged by the train for operating the slidable means and bring the throw means to train engaging position to cause the latter when engaged by the train to swing the gate to one position, means be- 120 125 130

7. In a railroad crossing gate, sectional spring connected rods disposed in bearings along the outer sides of the rails of the tracks, arched springs having their outer ends fixedly supported and their inner ends connected to the respective rods, said springs being in the path of contacting engagement with the tread surfaces of a rolling stock, spaced shafts journaled longitudinally at the railway crossing, grooved headed members thereon receiving in the grooves thereof the confronting ends of the respective shafts and in contacting engagement with the end walls of said grooves whereby when either spring is depressed the rods will exert a pressure against the heads to turn one of the shafts, means loosely arranged between the shafts for transmitting motion from one to the other shaft, angle levers secured to the shafts to the outer sides of the tracks, gates secured thereon, posts to the rear of the gates, links pivoted to the angle levers designed for contacting engagement with the posts, and buffer members for the gates when the latter are in closed position, as set forth. 70
8. In a railway crossing gate, rods journaled in bearings to the outer sides of the rails, each of said rods comprising sections, springs connecting said sections, arched springs having one end fixedly secured to a support and their other end pivotally connected with the respective rods, said springs being in the path of contact with the wheels of a rolling stock and designed upon depression to move one of the rods longitudinally in the direction of the crossing, shafts journaled transversely of the rails at the crossing, means on the shafts for contacting engagement with one of the rods for swinging said shafts, means between the shafts for transmitting motion from one shaft to the other, gates secured on the shafts outward of the tracks and operative by the turning of said shafts to obstructing and to non-obstructing positions, and signal means on said gates. 85
9. In a railway crossing gate, sectional spring connected rods journaled in bearings to the outer sides of the rails of the track, arched springs having their outer ends secured and their inner ends connected to the respective rods, shafts journaled transversely of the track at the crossing, a grooved headed member on each shaft receiving therein the confronting ends of the mentioned rods and designed when either rod is moved longitudinally by the depression of one of the arched springs by contact with the wheels of a rolling stock, to turn one of said shafts, slotted headed members arranged in spaced pairs and secured on the shafts intermediate of the tracks, oppositely directed angle rods in the grooves of each of said headed members whereby when 90
5. A means for operating a railway crossing gate by a train passing the crossing, including a gate, a pivoted leg on the outer end thereof, a shaft journaled in bearings, a connected member between the shaft and gate, a head on the outer end of the shaft, flexibly connected rods pivoted at opposite points to the head, arched springs, comprising gate throw members loosely connected to the respective rods, slideable members below the free ends of springs having depressed portions receiving the said ends therein whereby to sustain the spring members below train engaging position, arched spring members between the crossing and the throw members, and in train engaging position, yieldably connected rods between said spring members and the slideable gate throw supporting members, arched springs disposed outward of the gate throwing springs and in the path of contact with the train, flexibly connected rods loosely associated therewith, and means carried by said rods and loosely connected with the slideable gate throw supporting means, all as and for the purpose set forth. 100
6. In a railroad crossing gate, spring connected sectional rods disposed along the outer rails of tracks and also across the crossing, arched springs connected to the outer ends of said rods for contacting engagement with the tread of the wheels of railway stock approaching the crossing from either direction for imparting successive longitudinal movement to said rods in opposite direction, shafts, one of which being turned by one of said rods, means between the shafts for transmitting motion from one to the other, and crossing gates secured to and operated by said shafts. 105

either shaft is turned to impart a like motion to the second shaft, and gates operated on the turning of said shafts.

10. In a railway crossing gate, spring connected sectional rods disposed to the sides of the track, arched springs having their outer ends secured and their inner ends connected to the opposed pairs of sectional rods, said springs being in the path of contact with the 10 wheels of a rolling stock whereby a longitudinal movement will be delivered by the expansion of a spring to one of the rods, spaced shafts journaled transversely of the

track at the crossing, means on each shaft influenced by the longitudinal movement of one of the sectional rods on either side of the track for turning one shaft, means between the shafts whereby a simultaneous turning movement in opposite directions is imparted to the shafts, gates on the shafts, and means between the shafts at the crossing for imparting motion to the shafts independent of the first mentioned means.

In testimony whereof I affix my signature.

HUDSON BROWN.
